COOKING TOP COVER

George E. Pickup, Newark, Ohio, assignor to The Wehrle Company, Newark, Ohio, a corporation of Ohio

Application June 15, 1934, Serial No. 730,713

2 Claims. (Cl. 126—214)

This invention relates to cooking top covers and more specifically concerns improvements in cover constructions particularly adapted to gas ranges or the like where it is desirable to enclose the cooking plate so that the top of the range may be utilized as a table when the cooking plate is not in use.

A primary object is to provide a utility cover construction for the cooking tops of ranges wherein the cover is arranged to be quickly removed when the cooking top is to be used for cooking, and may be conveniently disposed of so as not to interfere with normal activity about the range, but is retained immediately at hand for replacement when desired.

Another object is to provide a cooking top cover which forms a normally connected part of the range but which may be removed and placed within a convenient part of the range so as to be completely out of the way, and to accomplish this result without affecting the normal appearance of the range.

Another object is to provide a disappearing cooking top construction for ranges together with associated parts to facilitate manipulation of the same.

Other objects and advantages will become apparent in the following description and from the accompanying drawing, in which:—

30 Fig. 1 is a fragmentary perspective view of a range and cooking top, showing the cover partly open.

Fig. 2 is a fragmentary transverse sectional plan view taken on line 2—2 of Fig. 1 and showing certain details of construction.

35 Fig. 3 is a vertical sectional view taken on line 3—3 of Fig. 2, and showing the arrangement of parts when the cover is in place over the cooking top.

40 Fig. 4 is a similar view showing the parts when the cover is disposed within the disappearing slide at the end of the stove.

A salient feature of the invention resides in the provision of a cooking top cover which, when the cooking top is in use for cooking, may be disposed of conveniently to one side of the cooking top where the cover will be out of the way but ready to be replaced quickly and with a minimum of effort. As a satisfactory manner of accomplishing the objectives of the invention there may be provided means below the surface of the cooking top for receiving the cover, and in order to facilitate manipulation of the cover, means may be provided for guiding the cover to and from said means for receiving the same.

Referring to the drawing, which shows an exemplary embodiment of the invention, a range 10 is provided with a cooking top comprising an angular upper peripheral frame 12 having inwardly offset flanges 13 forming a seat to receive a cooking plate 14. The upper surface of the cooking plate 14 is preferably, in a plane offset below the upper surface of the frame 12 so that a cover 15 which is preferably of about the same dimensions as the cooking plate will fit within the cooking plate opening in the frame 12 with its upper surface in the same plane as the upper surface of the frame.

Cooking top covers heretofore in use have either been bodily removable or have been hingedly connected to the range top to swing backwardly or to one side of the cooking plate. In the former instances the cover was subject to damage by careless handling, and disposal of the same while not in use created a problem; while in the latter cases the cover was often found to be an annoyance and a hindrance to the normal operations about the stove. By the present invention, however, means are provided for guiding the cover 15 when not in use into a convenient place at one side of the range, such, for example as into a receiving space within the body of the range. The cover is thereby completely out of the way, but may be readily withdrawn when desired for replacement over the cooking

30 plate. As a desirable means for accomplishing this purpose, there is provided a pair of substantially U shaped vertical guideway members 17 which are secured in spaced relation adjacent a side wall 18 of the range. These guideways 17 have lateral flanges 19 at their upper ends which are connected by means of suitable bolts 20 to the flanges 13 of the frame member 12, respectively adjacent the front and back of the range. At 40 vertically spaced points, the guideways 17 are attached to horizontal drawer slide members 22 the ends of which are rigidly secured in any suitable manner to the stove framework adjacent the front and back of the range.

45 A guide member 24 is connected adjacent one end of the cover 15 by means of one or more suitable hinges 26. In Fig. 2 one side of the guide 24 is shown for the purpose of illustration, the other side being substantially the same so that 50 a description of one will suffice for the other. An angular flange 27 on the edge of the guide is slidably received within the channel-shaped guideway 17, a sufficient clearance being maintained to permit free vertical reciprocation of

the guide. Thus, when the cover 15 is removed from the cooking top, the member 24 will move downwardly to guide the cover into the space between the guideways 17. A handle 28 is hingedly connected to the opposite end of cover 15 to facilitate lifting the same from the cooking top for insertion into the receiving space at the side of the range, and for withdrawing the same for replacement. The cover is preferably 10 enameled to present a pleasing and easily cleaned surface to harmonize with any desired decorative finish of the range.

The cover 15 is preferably of substantial construction and may be formed of suitable gauge 15 sheet metal capable of withstanding reasonable weight of objects so as to maintain a uniform plane in use. Stiffening flanges 29 may be formed about the edges of the cover to aid in rigidifying the same. These features, of course, 20 give a certain amount of bulk to the cover and in the absence of restraining means the force of gravity would tend to accelerate downward movement of the cover in the receiving space when the same is inserted therein. Repeated concus- 25 sion incident to the abrupt termination of its descent would in time deleteriously affect the contour and finish of the cover. Means are therefore provided to facilitate insertion of the cover into and its removal from the receiving means, 30 herein shown as a counterbalance 30 connected by means of a suitable rope or cable 31 to the guide member 24. One end of the cable 31 is attached to an eye bolt 32 in the upper edge of the counterbalance 30, and the other end of the 35 cable is engaged by a suitable engagement member 33 on a flange 34 on the lower edge of the guide member 24. The cable 31 is threaded over a pulley 35 which is rotatably mounted in a U shaped bracket 36 attached to a flange 37 formed at the top of side plate 18 of the range.

When the cover 15 is to be removed from the cooking top to be inserted into the receiving space therefor, the handle 28 is grasped and the cover raised to a vertical position whereupon its weight 45 added to the guide 24 will overcome the weight of the stationary counterbalance 30 and cause the guide 24 to descend slowly with the cover to the position shown in Fig. 4. The counterbalance 30 is preferably lighter than the combined 50 weight of the cover 15 and the guide member 24 so that the cover will remain in its hidden position until positively urged therefrom.

The counterbalance 30 is preferably elongated and flat in shape so as to require a minimum of 55 space for vertical movement, whereby the same may be slidably disposed in a relatively narrow space between the inner face of the side plate 18 of the range and flanges 38 on the guideways 17. As shown herein, the counterbalance may 60 be in the shape of a horizontally elongated, rectangular frame. Angular guides 39 are preferably secured adjacent the ends of the counterbalance 30 to prevent endwise movement of the same when it is raised or lowered. A stop 65 40 is secured to the lower ends of flanges 38 of the guideways 17 to prevent further descent of counterbalance 30, and may comprise an angle spanning the two guideways. A stop member 41 is 70 provided to limit downward movement of the

guide member 24 and the cover 15 in the guide-ways 17.

While the cover 15 has been described as being inserted into receptacle means at the side of the range, provision may as well be made to provide a space therefor adjacent another wall of the range such as at the back. The central part of the range, defined by a cross-member 42 of the frame 12, however, is generally traversed by gas pipes or the like and, consequently, it 10 does not ordinarily form a suitable place for the disappearing recess for the cover.

I will state in conclusion, that while the illustrated embodiment of the invention discloses a preferred form, it is to be understood that the 15 same may be considerably modified in detail without departing from the spirit and scope of the appended claims.

I claim as my invention:

1. In combination in a kitchen range, means 20 providing a body framework including angularly related vertical walls and a cooking top supported in a plane near the upper margins of said walls, a removable cover for said cooking top adapting the same to be used as a table, one 25 of said walls being spaced from said cooking top and providing a vertical pocket for receiving said cover when removed from the cooking top, a member hingedly connected to the edge of said cover and extending into said pocket for 30 guiding movement of the cover therein, counterbalancing means for effecting smooth and substantially effortless movement of said member and cover into or out of said pocket and including a flat weight connected with said member 35 and movable in a plane close to the plane of movement of said member and cover in said pocket, and guide means within said pocket defining the path of movement of said member and cover and including a part interposed between 40 said planes of movement for maintaining said weight permanently out of contact with the member or cover.

2. In combination in a kitchen range, means 45 providing a body framework including angularly related vertical walls and a cooking top supported in a plane near the upper margins of said walls, a removable cover for said cooking top adapting the upper part of the range to be used as a table, one of said walls being spaced from said 50 cooking top and providing a vertical pocket for receiving said cover when removed from the cooking top, a member hingedly connected to the edge of said cover and extending into said pocket for guiding movement of the cover therein, coun- 55 terbalancing means for effecting smooth and substantially effortless movement of said member and cover into or out of said pocket and including a weight connected with said member movable in a plane close to the plane of movement of said member and cover in said pocket, guide means within said pocket including a vertical part defining the path of movement of said member and cover and having a portion interposed between said planes of movement for maintain- 60 ing said weight out of contact with said member or cover, and means on said weight coactive with said vertical part for retaining said weight against transverse swinging movement.

GEORGE E. PICKUP.
